(57) CLAIM

I claim the ornamental design for the fully insulated snack holder, as shown and described.

DESCRIPTION

FIG. 1 is the front elevation view of a fully insulated snack holder with a zippered top, and side "D" rings for connection to a web shoulder strap for carrying, and top web strap for hand carrying showing my new design;

FIG. 2 is the rear view thereof, showing two web belt loops for carrying on a waistpack holder belt Or regular waist belt
FIG. 3 is a top plan view thereof, with a top web strap for hand carrying and two side "D" rings For connection to a web shoulder strap for carrying

FIG. 4 is a bottom plan view thereof, with two side "D" rings for connection to a web shoulder Strap for carrying

FIG. 5 is a side elevation plan view thereof, the opposite side being identical, showing web strap with "D" Ring, zippered top with web strap for hand carrying; and,

FIG. 6 is a top plan view thereof, with an unzipped top, showing the inside compartment of The snack holder.
The broken lines are to show stitching.
